UNITED STATES PATENT OFFICE

CALVIN Z. KROH, OF TOLEDO, OHIO

MOTOR-BOAT TOP

Application filed December 28, 1928. Serial No. 328,867.

My invention has for its object to provide a motor boat foldable or "one-man" top that is particularly designed to permit ready exit through the rear of the top. It is, as is well known, very desirable to provide free passage-way from one end of a boat to the other. Where tops are used to cover the cockpits of boats, it is ordinarily necessary to fold the top to enable one to pass from one end of the boat to the other end. This invariably locates the main bow and the folded parts of the top on the decking at the rear of the cockpit. If the decking is not of sufficient length, it invariably locates the folded top over the hatches located above the engine pit, which interferes with the opening and closing of the hatches. When the top is thus folded, it is necessary for individuals in passing from the cockpit to the engine pit, to walk over the folded top which, although it may be well folded, is often trampled on and, moreover, the folded top causes tripping of the individual particularly where there is any roughness of the sea.

My invention provides a means whereby a portion of the rear end of the top part of the top may be opened up as well as that part of the rear side of the top which is usually covered by the back curtain and thus there is afforded what might be termed a hatchway through the rear end of the top through which individuals may readily pass from the cockpit to the stern end of the boat. Foldable tops are necessarily of a light weight material and must be, particularly when used in connection with boats, exceedingly strong and tough as well as elastic, and, by my invention, this lightness of weight, elasticity and rigidity of construction is maintained. Thus the invention provides an exceedingly unique accomplishment with reference to top structures.

The invention may be contained in cover constructions of different forms wherein the covers are formed of flexible sheet material that is stretched or spread by foldable frames. To illustrate a practical application of the invention, I have selected a top construction that is particularly applicable to motor boats, as an example of the various embodiments

of my invention, and shall describe it herein-after. The structure selected is shown in the accompanying drawings.

Fig. 1 of the drawings illustrates a perspective view of a boat to which the top, embodying my invention, may be applied and illustrates the general arrangement of the parts and the utility of the construction. Fig. 2 is a perspective view of the rear part of the top. Fig. 3 illustrates a hinged section of the rear or main supporting bow of the top when partially opened. Fig. 4 illustrates a top side of the section when closed. Fig. 5 illustrates an inner side view of the bow when the hinged section thereof is closed. Fig. 6 illustrates a view of the bow when the hinged section is wide open. Fig. 7 illustrates a perspective view of the interior of the rear part of the top showing the free passage-way through the top. Fig. 8 is a view of a section of the bow and illustrates the manner in which the sheet material of the top is connected to the hinged section of the bow.

In the particular form of construction shown in the drawings, the top 1 is supported by a main bow 2 to which is connected, in any suitable manner well known in the art, auxiliary bows 4 that coact with the main bow 2 to stretch or maintain the sheet material in its stretched or open position with reference to the cockpit 5 of the boat 6. The boat may be provided with the usual decking 7 in which may be located the usual hatches 8 for access to the engine. In order to afford free passage-way from one end of the boat to the other, the top 1 is provided with an opening that forms a hatchway whereby individuals may readily pass through the top without folding it up and laying it upon the decking 7.

The top 1 is provided with a curtain 10 that extends from the decking 7, or from an auxiliary rear curtain, over the main bow 2 forwardly to a point where it is secured to the body of the sheet material of the top. The curtain 10 is, preferably, of a width so as to well overlap the side portions 11 of the body of the sheet material and the stays 12. The curtain may be secured in position by suitable buttons 13 of the form commonly used

in securing parts of tops together and may be distributed over these parts as may be desired.

The main bow 2 is provided with a hinged section 15 that may be readily opened and folded back towards one of the legs 16 of the body which affords a free passage-way through the rear side of the top. Preferably, the rear bow is formed quintalateral to provide two parallel sides 17 and 18 and two sides 19 and 20 that extend substantially in the planes of the rear side of the top and the top side of the top. The parallel surfaces 17 and 18 on the main bow are joined by a fifth surface 21 that is at right angles to the parallel surfaces 17 and 18. The surface 21 is located at right angles to a line extending diagonally downward into the cockpit and, consequently, this affords a means whereby the section may be hingedly connected to the body of the main bow and so that the section may be swung diagonally downward beneath the top. Thus the hinge 22 may be connected to the body of the main bow and to the section 15. Preferably, one of the leaves or wings of the hinge 22 is provided with flanges 23 that overlap the end portions of the section 15 and one side part of the main bow 2 and fit the surfaces 17 and 18. The other end of the section 15 is provided with a suitable rigid hasp 24 that is located on the surface 21 and is secured to the section 15 and so as to overlap the end of the other side part of the main bow 2 along the surface 21. The rigid hasp 24 is also provided with flanges 25 that fit the surfaces 17 and 18 of that end of the section 15 and of the said other side part of the bow 2. When the hasp 24 is secured to the body of the bow 2, the overlapping parts afford an exceedingly rigid construction closed.

In the form of construction shown, the end of the rigid hasp 24 may be provided with an opening 26 and a thumb screw 27 may be inserted through the opening 26 and screwed into the opening 29 formed in the end of one of the side parts of the main bow 2. The thumb screw 27 may be chained to the section 15 or to the hasp 24 by means of the chain 28. When, therefore, the section 15 is closed and secured by the thumb screw 27, the bow 2 will be formed complete for retention of the curtain 10 in its position when it is replaced over the section and drawn down and secured in position relative to the stays 12 by means of the buttons 13.

In order to provide a means for temporarily securing the section independent of the screw 27, the ends of the section 15 and of the parts of the bow 2, are cut on the diagonal to form the diagonally located surfaces 35 that are inclined downwardly and inwardly with respect to the interior of the top. When, therefore, the section 15 is closed, the parts of the body of the bow 2 may be sprung

laterally whereby the corners of the section, and a part of the bow, will pass each other and the elasticity of the connected bows and the sheet material will cause its return, and the end surfaces of the section 15 and the parts of the main bow will interengage and prevent the section 15 from dropping from its position, notwithstanding the omission of the insertion of the thumb screw 27.

The curtain 10 may be drawn over the section 15 when it is desired to close the passage-way through the rear end of the top. The curtain 10 may be provided with a flap 36. As shown in Fig. 8 of the drawings, the flap 36 may then be drawn around the under side of the section 15 and the end of the parts of the bow 2 and may be secured by suitable buttons 37 located on one of the inner surfaces, such as the surface 21 of the bow 2 and of its section 15.

I claim:

1. In a foldable top for boats, a plurality of bows, a sheet material spread by the bows, the rear bow having a section, a hinge for connecting one end of the section to the body of the last named bow, the hinge having a pair of flanges for overlapping the joint ends of the section and the body of the bow, the other end of the section having a rigid hasp for connecting the said other end to the body of the bow, the hasp having flanges for overlapping the ends of the section and the body of the bow at the hasp, the last named end of the section and the end of the part of the body of the bow located at the hasp formed to have inclined surfaces that extend diagonally downward and inwardly with respect to the interior of the top for interconnecting the section with the body of the bow by the elasticity of the top, the top side of the top and the rear side of the top having an opening and a curtain secured near the forward edge of the opening and extending rearwardly over the section and downwardly to cover the said opening, a flap connected to the curtain, means for connecting the flap to the section to secure the curtain to the bow, and means for securing the edges of the curtain to the body of the sheet material.

2. In a foldable top for boats, a bow, a sheet material spread by the bow, the sheet material having an opening, a curtain covering the opening, the bow having a removable section to afford a free passage-way through the top.

3. In a foldable top for boats, a plurality of bows, a sheet material spread by the bows and having an opening, one of the bows having a removable section hingedly connected at one end to the body of the bow, means for securing the other end of the section to the body of the bow, a curtain covering an opening formed in the top to provide a free passage-way for individuals through the top part of the top and the rear side of the top.

4. In a foldable top for boats, a plurality of bows, a sheet material spread by the bows, one of the bows having a hingedly connected section, means for securing one end of the section to the body of the last named bow, the sheet material having an opening through the top part of the top, and a curtain extending from the top side of the top and over the section of the bow to close the opening.
5. In a foldable top for boats, a plurality of bows, a sheet material spread by the bows, one of the bows having a hingedly connected section, means for securing one end of the section to the body of the last named bow, the sheet material having an opening through the top side of the top and the rear side of the top, a curtain extending from the top side of the top and over the section of the bow and over a part of the rear side of the top to close said opening.
- 10 6. In a foldable top for boats, a plurality of bows, a sheet material spread by the bows, the rear bow having a removable section, means for connecting the ends of the section to the body of the bow, the sheet material having an opening in the top side of the top and the rear side of the top, and a curtain connected near the forward edge of the opening and extending over the section, and means 15 for securing the curtain to the body sheet material of the top and to the section.
